INVENTOR.

Sidney Parker.

United States Patent Office.

SIDNEY PARKER, OF CHICAGO, ILLINOIS.

Letters Patent No. 85,758, dated January 12, 1869.

IMPROVED RAILWAY-FROG.

The Schedule referred to in these Letters Patent and making part of the same.

To all whom it may concern:

Be it known that I, SIDNEY PARKER, of Chicago, in the county of Cook, and State of Illinois, have invented certain new and useful Improvements in Railroad-Frogs; and I do hereby declare that the following is a full, clear, and exact description thereof, reference being had to the accompanying drawings, making part of this specification, and to the letters of reference marked thereon, like letters indicating like parts whenever they occur.

To enable others skilled in the art to construct and use the invention, I proceed to describe it.

My invention consists in making a bed-piece or frame of a single piece of wrought-iron, of proper shape, to receive and hold the rails, and fitting thereto rails of hammered steel, with a plate, also of wrought-iron, under the centre of the bed-piece, and of the same width, securely bolted or fastened to the bed-plate or frame.

The point or centre of the frog is made of hammered steel, passes through the bed-plate, and is bolted or fastened to the piece of wrought-iron under the bed-plate.

I first construct a bed-piece or frame, L, in fig. 2, side elevation, of wrought-iron, of proper length, and width, and thickness.

Under the centre of the bed-plate is placed a plate of wrought-iron, marked M, in fig. 2, side elevation, of the same width as the bed-plate, and of proper length.

At each end of the bed-plate is a cast or wrought-iron chair, or partly of both, to receive the end of the rail, as shown in N, on fig. 2, side elevation, and of the shape shown in F, fig. 4, end elevation, to B B.

A plate of wrought-iron, marked O, on fig. 2, side elevation, is placed under and used as the bottom of the chair, and is secured to the chair, bed-plates, and rails by rivets, as shown in fig. 8, inverted plan.

P, on inverted plan, fig. 8, is a square hole, punched through the wrought-iron plate forming the base of the chair, through which one or more spikes are driven into the ties to hold rails.

I and J, as shown on fig. 1, are hammered-steel rails, secured by rivets.

H, as shown on fig. 1, is a hammered-steel point let through the bed-plate, and fastened to the wrought-iron plate under the centre of bed-plate as before described, by rivets.

G, on same figure, is a hammered-steel or wrought-iron base, secured to bed-plates by wrought-iron rivets or bolts.

F and K, on fig. 1, are chairs made partly of cast and partly of wrought-iron, or wholly of either, and securely fastened to the bed-plates by rivets.

Figure 1 is the plan.

Figure 2 is side elevation.

Figure 3 is section through a a, fig. 1.

Figure 4 is end elevation to B B of fig. 1.

Figure 5 is section through C C to fig. 1.

Figure 6 is section through D D of fig. 1.

Figure 7 is end elevation to E E, fig. 1.

Figure 8 is an inverted plan.

Having thus described my invention,

What I claim, is—

A railroad-frog, consisting of the wrought-iron bed-plate L, the wrought-iron plate M under its centre, the hammered-steel point H, let through the bed-plate and fastened to M, the hammered-steel rails I and J, the cast-iron chair F, with wrought-iron base O, the whole combined and constructed as herein shown.

Chicago, September 2, 1867.

SIDNEY PARKER.
